Patented Sept. 28, 1926.

UNITED STATES PATENT OFFICE.

ELLIS HARTLEY, OF WHITINSVILLE, MASSACHUSETTS.

ROLL CLEANER FOR SPINNING AND LIKE MACHINES.

Application filed January 11, 1926. Serial No. 80,443.

My invention relates to an improved device designed for application to and use in combination with the bottom delivery rolls of spinning machines, with the object of preventing roller laps or fibre being wound around such rolls, and whereby the rolls are maintained in a perfectly clean condition at all times.

The invention comprises a reciprocating bar on one side of which is fixed a strip of felt or other fibrous material. The bar is slidably mounted in spring controlled bearings adjacent to the roll so that the strip of felt is in rubbing contact with the surface of the roll and a requisite amount of pressure between the clearer and roll is maintained by the action of the springs on the bearings.

Referring to the drawings which form a part of this specification—Figure 1 is a sectional elevation on line 1—1 in Figure 2 of a fragmentary portion of a worsted spinning frame roll stand showing a series of delivery rolls stationed thereon with my improved clearer applied thereto. Figure 2 which is a plan view of Figure 1, shows my improved means for imparting a reciprocating movement to the clearer bars. Figure 3 is an enlarged rear elevation of the reciprocating means. Figure 4 is an enlarged sectional end elevation on line 4—4 of Figure 2 showing the clearer bar in its proper relation to the surface of the roll. Figure 5 is a rear elevation of Figure 4. Figure 6 is a sectional elevation on line 6—6 of Figure 2 showing a fragmentary view of the lever and its fulcrum and connection with the roving traverse motion.

In the embodiment of the invention shown in the accompanying drawings, it is illustrated as applied to the bottom carrier rolls of an ordinary and well known type of worsted spinning machine. Inasmuch as the invention appertains to the roll cleaning device, and as the construction, arrangement and operation of worsted spinning machines are well known, no description of the latter is deemed to be necessary. The said roll cleaner comprises a bar 10 of either wood or metal having a strip of fibrous material 11 fixed thereto in rubbing contact with the surface of the drawing roll 12. The bar is slidably mounted in bearings 13 swingable on trunnions 14 on each side of the bearing and supported by

the spring hangers 15 fixed to the carrier roll bearing brackets 16 which are slidably mounted on the roll stands 17. The resiliency of the spring hangers forces the bar into contact with the roll surface, thereby maintaining the latter in a clean condition at all times. The operation of cleaning the roll is rendered more effective by imparting a reciprocating motion to the bar 10 which I accomplish by suitable connecting means between the bar and some continuous moving part of the machine, preferably the roving traverse motion commonly used on spinning machine such as shown in Figure 3, wherein the back drawing roll 18 transmits rotary motion to the shaft 19 by means of the worm 20 fixed to the roll coacting with the gear 21 to said shaft, the shaft being supported in the hanger 22 fixedly connected to the back bar 23 which is bolted to back roll brackets 24 slidably mounted on roll stands 17. A cam 25 fixed to the shaft 19 coacts with the follow roll 26 rotatable on a stud 27 fixed to the roving traverse bar 28 which is slidably mounted in bearings formed in the bases of the back roll brackets 24. The follow roll is held in constant contact with the working surface of the cam by the tension spring 29 connected between traverse bar 28 and stationary back bar 23. By this construction the roving traverse bar slides back and forth in its bearings to an extent determined by the eccentricity of the cam.

In order to impart a reciprocating motion to the clearer bars 10 a finger 30 fastened to the roving traverse bar 28 coacts with a slot 31 in the rear end of a lever 32 which is supported on a stud 33 swingably mounted in an ear 34 fixed to the back bar 23. The front end of said lever coacts with finger 35 in a fixed relation with the clearer bar. By this construction the reciprocating motion of the roving traverse bar imparts a like motion to the clearer bar with the result that the surface of the roll is kept free from lint and oil which if allowed to accumulate would be detrimental to the quality of yarn being produced.

I claim:

A drawing roll cleaner for spinning machines comprising a bar having a strip of fibrous material affixed thereto in rubbing contact with the surface of the drawing roll, movable bearings in which the bar is slid.

ably mounted, a spring coacting with each bearing to press the bar against the surface of the roll, a lever, a fulcrum on which said lever is swingable, a connecting finger between the clearer bar and the lever, and a connection between the lever and the moving traverse bar whereby the reciprocating

movement of the latter actuates the lever and imparts a reciprocating motion to the clearer bar.

In testimony whereof, I have signed this specification.

ELLIS HARTLEY.
